[57] CLAIM

The ornamental design for a combined toy plane and video game, as shown and described.

DESCRIPTION

FIG. 1 is a perspective view of a combined toy plane and video game showing my new design;

FIG. 2 is a front elevational view thereof;

FIG. 3 is a left side elevational view thereof which is a mirror image of the right side;

FIG. 4 is a rear view thereof;

FIG. 5 is a top plan view thereof;

FIG. 6 is a bottom plan view thereof;

FIG. 7 is a perspective view thereof with the top of the toy plane raised;

FIG. 8 is a front view of the toy plane of FIG. 7; and,

FIG. 9 is a side view of the toy plane of FIG. 7.
